(57) **CLAIM**

The ornamental design for an orbicular dodecahedron model as shown and described.

DESCRIPTION

The patent or application file contains at least one drawing executed in color. Copies of this patent or patent application publication with color drawings will be provided by the Office upon request and payment of the necessary fee.

FIG. 1 shows a first view of an orbicular dodecahedron model in an unfolded configuration according to a first embodiment.

FIG. 2 shows a top view of the orbicular dodecahedron model in a folded configuration according to the first embodiment.

FIG. 3 shows a bottom view thereof.

FIG. 4 shows a front view thereof.

FIG. 5 shows a back view thereof.

FIG. 6 shows a left side view thereof.

FIG. 7 shows a right side view thereof.

FIG. 8 shows a first view of the orbicular dodecahedron model in an unfolded configuration according to a second embodiment.

FIG. 9 shows a top view of the orbicular dodecahedron model in a folded configuration according to the second embodiment.

FIG. 10 shows a bottom view thereof.

FIG. 11 shows a front view thereof.

FIG. 12 shows a back view thereof.

FIG. 13 shows a left side view thereof; and,

FIG. 14 shows a right side view thereof.

The red lines showing edges to link the unfolded configurations to the folded configurations are disclaimed.

The use of greyscale is to show color contrast.

(Continued)

The broken lines shown in the claimed design are surface indicia and do form part of the claimed design.
